[57] CLAIM

The ornamental design for a combined Christmas tree angel ornament and smoke alarm, as shown and described.

DESCRIPTION

FIG. 1 is a front elevational view of the combined Christmas tree angel ornament and smoke alarm showing our new design;

FIG. 2 is a rear elevational view thereof;

FIG. 3 is a right side view thereof;

FIG. 4 is a left side view thereof;

FIG. 5 is a top plan view thereof; and,

FIG. 6 is a bottom plan view thereof.

The broken lines showing in FIG. 2 are apertures interior of the ornament and form no part of the claimed design.
